UNITED STATES PATENT OFFICE

GEORGE SPATTA, OF BUCHANAN, MICHIGAN, ASSIGNOR TO CLARK EQUIPMENT COMPANY, OF BUCHANAN, MICHIGAN, A CORPORATION OF MICHIGAN

MACHINE AND METHOD OF FLATTENING FLANGES OF BANJO FRAMES

Application filed February 15, 1930. Serial No. 428,653.

This invention relates to the machine and method of flattening flanges of banjo frames.

In my copending application, Serial No. 416,537, filed December 26, 1929, I disclosed 5 a method of making axle housings from a tubular blank, in which the blank is slotted, and shaped to form a flanged cylindrical banjo disposed in the central portion of the housing with its axis at a right angle to the axis 10 of the housing.

The operation of forming the flanged banjo housing, more fully disclosed in my copending application, Serial No. 426,545, filed Feb. 7, 1930, includes the step of folding the edges 15 of the central wall sections of the blank over at right angles to the wall to form the flanged banjo, and simultaneously spreading these walls to make the banjo cylindrical.

This operation leaves the flanges somewhat 20 irregular, and it is therefore necessary to straighten these flanges so that they will be perfectly flat surfaces to which the cover of the housing and drive shaft casing bracket may be securely attached and with which 25 they will form grease-tight joints.

The present invention relates to a method 30 of and machine for performing the flattening operation on the flanges of such a housing, and for performing similar operations upon similar blanks.

In the preferred embodiment of the instant invention, a hammer is disposed with its axis vertical and is reciprocated longitudinally of that axis. The hammer may be mechanically 35 driven or if desired may be an air hammer or any other type of hammer capable of delivering a large number of blows per minute. Since the wall sections of the flanges of a housing of this type are relatively thin, 40 the amount of force required of the hammer is not great, and it is therefore preferable to provide a relatively small hammer which delivers several hundred blows per minute during its operation.

The axle housing is approximately five feet long, and the cylindrical banjo in the center is in the neighborhood of one foot in diameter. It is necessary, therefore, to move 45 the housing in a circular path having a radius of approximately one-half a foot to

bring every portion of the flange into engagement with the reciprocating hammer. Because of the length of the housing, it is obviously inconvenient to rotate it about the axis of the hammer simultaneously with the 55 circular movement that brings the flange into engagement with the hammer, and I have, therefore, provided a new and improved anvil mounting which permits rotating the housing with respect to the hammer in a 60 translatory movement over a path of the proper radius. This obviates the necessity of building the machine with sufficient clearance to permit the end sections of the blank to pass a frame of the machine, and since 65 the operator can manipulate the blank while standing in close proximity to the hammer, the operation of the machine is speeded up appreciably and the cost of performing the 70 operation is thereby materially reduced.

In the preferred form of my invention, the anvil mounting comprises three ball races disposed with their centers lying on the circumference of a circle whose center coincides with the axis of the hammer, the center of 75 the ball races being located at the apexes of an equilateral triangle which is circumscribed by that circle.

To further guide the anvil block in its travel around the axis of the hammer, I 80 have provided a pin in the anvil whose axis coincides with the axis of the cylindrical portion of the housing that is to be flattened by the machine, said pin projecting into a circular slot in the stationary plate of the 85 machine. The circular slot is located with its axis coinciding with the axis of the hammer, so that the engagement of the pin on the anvil with the slot on the stationary portion of the machine guides the anvil. The 90 anvil is supported solely by balls located in the ball races there being one ball in each race.

Because of the differential action of the 95 ball rolling in the stationary race in the bed plate of the machine and in the movable race in the anvil block, the diameter of the ball races equals the radius of the path in which the anvil block will be moved and by suitable selection of the ball races, the 100

movement of the anvil can be accurately controlled with respect to the reciprocating hammer.

Now to acquaint those skilled in the art with the teachings of my invention reference is made to the accompanying drawings in which a preferred embodiment of it is shown by way of example, and in which:

Figure 1 is a side elevational view of a complete machine with a blank in place in it;

Figure 2 is a plan view of the anvil arrangement of the machine shown in Figure 1, taken substantially along the line 2—2 of Figure 1 looking in the direction of the arrows;

Figure 3 is a cross sectional view through the anvil taken along the line 3—3 of Figure 2 looking in the direction of the arrows;

Figure 4 is a detailed plan view of the anvil supporting structure taken along the line 4—4 of Figure 1 looking in the direction of the arrows;

Figure 5 is a cross sectional view through the anvil and blank taken along the line 5—5 of Figure 1 looking in the direction of the arrows.

The machine comprises a framework having a pedestal 1 supported on a suitable footing 2, and terminating in an overhanging arm 3 to which the hammer structure 4 is attached.

Immediately beneath the hammer 4 is a stationary bed plate 5 which is mounted upon the pedestal 1 and made adjustable with respect thereto in any convenient manner such as by the screw 6 and lock nut 7. The bed plate 5 serves as a mounting for the anvil upon which the work is mounted, and must be sufficiently adjustable vertically to bring the work into proper registration with the hammer.

The hammer 4 is operated by a cam and lever or by a connecting rod connected to the pulley wheel 9, which pulley wheel is rotated in any convenient manner such as by an electric motor, not shown. Rubber blocks 10 and 11 are attached to the rod 8, and the pin 12 of the operating lever 13 interposed between the blocks 10 and 11 so that the lever is oscillated about its pivot 14 by an oscillation of the rod 8.

Lever 13 is connected to the hammer 4 by a rod 15, and pivoted to the portion 3 of the frame by the pivot 14 so that an oscillation of the lever 13 will produce an oscillation of the hammer in a vertical direction.

The operation of the hammer is controlled by a clutch 16 which is operated in a convenient manner as by the foot lever 17 to permit the operator to start and stop the oscillatory movement of the hammer at will. The particular type of clutch and drive of the hammer is not of the essence of the present invention and may be modified greatly

within the teachings of the invention. If desired, an air hammer may be substituted for the mechanical hammer shown, or any other suitable type of high speed hammer may be employed.

As will be seen in Figures 1, 3 and 4, the bed plate 5 of the machine is provided with a flat top portion 20 which is rigidly attached to the bed plate 5 in any convenient manner such as by the screws 21. Located in the upper surface of this plate is a centrally located circular opening 22 whose walls are perpendicular to the upper face of the plate 20. Centrally located in this circular groove 22 is a cylindrical pin 23 which together with the opening

22 forms an annular groove of rectangular cross section whose center coincides with the center of the plate 20. The pin 23 is provided with an extension 28 which registers with a counterbore 29 in the plate 5 to center the bed plate in the machine. The axis of the counterbore 29 coincides with the axis of the hammer, and the bed plate 20 is thereby centered on that axis.

Three stationary ball bearing races 24, 25 and 26 are located around this annular groove with their centers positioned on the circumference of a circle 27 whose center coincides with the center of the opening 22 and the pin 23, and consequently with the axis of the hammer.

As will be best seen in Figures 3 and 5, the ball race 25 is a hardened disc set into a circular pocket 30 formed in the upper surface of the plate 20. A round bottom annular groove 31 is located in the upper surface of the plate 25, the center of this groove coinciding with the center of the plate 25 and lying on the circle 27. This annular groove forms a race in which the ball 32 rotates as will presently appear. The ball races 24 and 26 are similarly constructed.

The anvil block 40 is supported on the plate 20 by the ball 32 in the ball race 25 and the ball 33 in the ball race 24 and the ball 34 in the ball race 26. The ball 32 registers with a second ball race 25' which is constructed identically with the race 25 and located in the pocket 41 in the lower surface of the anvil block 40. The ball 33 registers with a race 24' which is identical with the race 24 and located in the pocket 42 in the anvil block 40, and the ball 34 registers with a race 26' located in the pocket 43 in the anvil block. The pockets 41, 42 and 43 are similarly located with their centers on the circumference of a circle whose diameter is equal to the diameter of the circle 27, so that the ball races accurately register with each other when the block 40 is set upon the plate 20. The races 25', 24' and 26' are held in their respective pockets in the anvil block 40 in any convenient manner, such as by a press fit, which is sufficient since the weight of the anvil block 40 bearing on

130

the races tends to hold them securely in their respective pockets.

The anvil block 40 is provided with a central opening 44 whose center coincides with the center of the circle on which the centers of the ball races 24', 25' and 26' are located, the hole 44 being provided with a counterbore 43 adjacent the upper surface of the block. A pin 46 fits into this hole, and has a shoulder portion which registers with the counterbore to hold the pin in place. At the upper end of the pin is a projection 47 which is of smaller diameter than the shoulder portion 46, and at the bottom end of the pin is a projections 48 which is of smaller diameter than the pin portion 46. A roller 48' is fitted over this small diameter projection 48 and held thereon by a washer 49' and nut 49, the roller engaging the walls of the slot 22 and the outside surface of the pin 23 in the bed plate 20 to guide the anvil block 40 in its movement over that bed plate.

The upper end 47 of the pin 46 projects through a central opening in the anvil 50, to position that anvil accurately on the anvil block 40 with its center coinciding with the central axis of the pin 46. The anvil block 50 comprises a generally circular member having a projecting annulus or flange 51 upon which the blank rests and against which it is pressed by the action of the hammer. The anvil is held on the block 40 in any preferred manner such as by the bolts 52, which also serve to hold the pin 43 in place in the block 40. Preferably the anvil 50 is constructed of hardened steel with the upper surface of the annular projection 51 ground smooth and flat.

The work that is to be flattened in the machine is held on the anvil block 50 by clamps 53 and 54, the outer ends of which fit over the top of bolts 55 and 56, respectively, and are held thereon by bolts 57 and 58 which are provided with nuts 59 and 60 that are tightened to cause the clamps 53 and 54 to exert pressure on the upper ends of the pins 55 and 56 and on the blank in the machine. If desired, coil springs 61 and 62 may be placed around the bolts 59 and 60 to lift the clamp members 53 and 54, respectively, off of the blank when the nuts are loosened, to thereby facilitate ready removal of the blank from the machine.

The upper surface of the anvil block 40 is provided with a plurality of sockets 63 and 64 into which are placed coil springs 65 and 66, the upper ends of these springs bearing against the flanged head of positioning pins 67 and 68. These pins extend up inside of the annular projection 51 of the anvil, and serve to position the blank on the anvil and beyond its upper surface a distance greater than the thickness of the flange 70 to a position high enough to catch the edge of the flange even though the edge be distorted by

bearing against the inside edge 69 of the flange portion 70 of that blank. Preferably three positioning pins of this type are provided, although a larger or smaller number may be used as required to properly position the blank or the anvil.

The hammer 4 is provided with a circular head 71 which has a flat bottom face that is brought into engagement with the flange 70 of the blank. The stroke of the hammer 4 is sufficiently small that when it is raised it does not strike against the upper surface of the flange, and with the blank properly placed in the web section 72 of the blank clears the peripheral edge of the hammer 71. As the hammer is reciprocated and the anvil rotated, the flange 70 is flattened in the obvious manner.

When the hammer 71 strikes the upper ends of the pins 67 and 68, those pins are pressed down into the pockets 63 and 64, respectively, sufficiently far to permit their upper ends to fall below the surface of the flange 70 so that the hammer may flatten the flange at that point. When the hammer is removed, the springs 65 and 66 raise the pins again, the motion being limited by their flanged heads striking against the underside of the anvil plate 50.

With the blanks so positioned in the machine, the hammer is started by the operator pressing the lever 17, and the operator then moves the blank, the anvil 50, and the anvil block 40 in a circular translatory motion, around a circle whose center coincides with the center of the hammer 4. By proper design of the ball races 24, 25, and 26, and their companion races and of the annular groove 22 in the stationary block 20, the path of the anvil and blank can be governed so that the peripheral edge of the hammer is always close to yet not touching the web section 72 of the blank. As the anvil is moved, through this path, parts of the flange 70 are successively brought under the hammer 71 until the entire flange has been flattened by the action of the hammer.

The nuts 59 and 60 are then loosened and the clamping plates 53 and 54 removed from the blank, and the blank turned over and the operation repeated on the other flange 74 of that blank.

It will be noted that during the movement of the blank in the machine, the axis of the blank is always parallel to its original position in the machine and, therefore, it is only necessary to provide clearance between the axis of the hammer and the frame 1 of the machine sufficient to permit the anvil to move around in the path just described, since the end sections of the blank project laterally from the machine and are not rotated during the operation of the machine.

While I have illustrated the machine specially designed to flatten the banjo section of

a rear axle housing of an automobile, I have done so by way of example only as the invention may be adapted to a number of uses of which the one shown is but an example. I am not, therefore, to be limited to the specific details of the disclosure, but rather am to be limited by the scope of the appended claims.

Having thus complied with the statutes and shown and described a preferred embodiment of my invention, what I consider new and desire to have protected by Letters Patent is pointed out in the appended claims.

What is claimed is:

1. The method of engaging a piece of work having a flanged cylindrical portion with a hammer having a circular head which is reciprocated along a fixed vertical axis, which comprises, registering the work with the hammer, bringing a point of the cylindrical portion of the work against the hammer, and moving the work in a circular path around the hammer with a translatory motion which keeps a point on the work touching the hammer.

2. The method of engaging a piece of work having a flanged cylindrical portion with a hammer having a circular head which is reciprocated along a fixed vertical axis, which includes the following steps, viz., placing the work on a member movable with respect to the axis of the hammer eccentrically of the hammer, adjusting the work to bring a point of its cylindrical portion into registration with the hammer, clamping the work to the member to maintain that adjustment, and moving the work and member in a circular path around the hammer with a translatory motion which keeps a point on the work registered with the hammer.

3. A support for a block which permits movement of the block in a circular path without turning, which comprises a plurality of ball races of diameters equal to the radius of the path, a single ball in each race, and means for guiding the block in the path.

4. A support for holding a block on a bed plate which permits moving the block in a circular path on the plate without turning which comprises, ball races disposed half in the block and half in the plate with their centers disposed on a circle whose center coincides with the center of the circular path, a ball in each race, and guide means carried by the block and registering with the plate to guide the block with respect thereto.

5. A support for holding a block on a bed plate which permits moving the block with a translatory motion through a circular path on the plate, consisting of ball races of diameters, equal to the radius of the path of movement formed half in the block and half in the plate, and a single ball in each race.

6. A support for holding a block on a bed plate which permits moving the block with a translatory motion through a circular path

on the plate, consisting of three ball races of diameters equal to the radius of the path of movement formed half in the block and half in the plate and located equidistantly from each other and from the center of the block, and a single ball in each race.

7. A support for holding a block on a bed plate which permits moving the block with a translatory motion through a circular path on the plate, consisting of three ball races of diameters equal to the radius of the path of movement formed half in the block and half in the plate and located with their centers on the points of an equilateral triangle, and a single ball in each race.

8. A flange flattening machine comprising a stationary bed plate, a movable bed plate mounted thereon and adapted to be moved in translatory motion over a circular path on the stationary plate, an annular anvil mounted on said movable plate with its axis lying on the path of motion, clamps for holding work on the anvil, a hammer disposed with its axis coinciding with the center of said path, and means for reciprocating said hammer longitudinally of its axis.

9. A flange flattening machine comprising a stationary bed plate, a movable bed plate mounted thereon and adapted to be moved in translatory motion over a circular path on the stationary plate, a hardened anvil mounted on said movable plate, clamps for holding work on the anvil, a hammer disposed with its axis coinciding with the center of said path, and means for reciprocating said hammer longitudinally of its axis.

10. A flange flattening machine comprising a stationary bed plate, a movable bed plate mounted thereon and adapted to be moved in translatory motion over a circular path on the stationary plate, a hardened annular shaped anvil mounted on said movable plate with its center on the path of said motion, clamps for holding work on the anvil, a hammer disposed with its axis coinciding with the center of said path, and means for reciprocating said hammer longitudinally of its axis.

11. A flange flattening machine comprising a stationary bed plate, a movable bed plate mounted thereon and adapted to be moved in translatory motion over a circular path on the stationary plate, an annular anvil mounted on said movable plate with its axis coinciding with the path of motion, clamps for holding work on the anvil, a hammer consisting of a circular head mounted on a cylindrical shank, means for mounting said hammer with its axis coinciding with the center of said path, and means for reciprocating said hammer longitudinally of its axis.

12. A flange flattening machine comprising a stationary bed plate, a movable bed plate mounted thereon and adapted to be moved in translatory motion over a circular path on

80

85

90

95

100

105

the stationary plate, an annular anvil mounted on said movable plate with its axis coinciding with the path of motion, clamps for holding work on the anvil, a hammer consisting of a circular head mounted on a cylindrical shank, means for mounting said hammer with its axis coinciding with the center of said path, a lever connected to said hammer and pivoted to the machine, and means for oscillating said lever to move the hammer longitudinally of its axis.

13. In a flattening press, a hammer, an anvil, means for moving said anvil in a circular path around said hammer, said means including ball races in the anvil having diameters equal to the radius of said path, balls in said races, and stationary races of equal diameters.

14. In a flattening press, a hammer, a circular anvil, means for moving said anvil around said hammer so that its center describes a circular path around the axis of the hammer, said means including ball races in the anvil having diameters equal to the radius of said path, balls in said races, and stationary races of equal diameters.

15. In a flange flattening machine, a stationary bed plate containing a circular opening, a pin of diameter smaller than said opening concentrically located in the opening to form an annular groove in the plate, a plurality of ball races located in said plate with their centers on a circle that is concentric with the center of said opening and pin, an anvil block, a plurality of ball races in said block disposed with their centers on a circle of the same radius as the circle through the centers of the races in the plate, a ball in each race in the plate and registering with the corresponding race in the anvil to support the anvil on the plate, and a pin projected from the anvil and registering with the groove in the plate to guide the anvil with respect to the plate.

16. In a flange flattening machine, a stationary bed plate containing a circular opening, a pin of diameter smaller than said opening concentrically located in the opening to form an annular groove in the plate, a plurality of ball races located in said plate with their centers on a circle that is concentric with the center of said opening and pin, an anvil block, a plurality of ball races in said block disposed with their centers on a circle of the same radius as the circle through the centers of the races in the plate, a ball in each race in the plate and registering with the corresponding race in the anvil to support the anvil on the plate, and a pin projected from the anvil with its axis registering the center of the circle through the ball races in the anvil, and registering with the groove in the plate to guide the anvil with respect to the plate.

17. In a flange flattening machine, an anvil

block having an annular working surface, a hammer having a circular head, means for holding the block in juxtaposition to the hammer including a ball race having a diameter equal to the difference between the radius of said anvil and the radius of the hammer, a ball in said race, and a second and stationary race of equal diameter.

18. In a flange flattening machine, an anvil block having an annular working surface, a hammer having a circular head, means for holding the block in juxtaposition to the hammer including a plurality of ball races each having a diameter equal to the difference between the radius of said anvil and the radius of the hammer, a ball in each of said races, and a plurality of stationary races of equal diameters.

19. In a flattening machine, a frame, a hammer mounted at the upper end of the frame with its axis perpendicular, means for reciprocating said hammer, a bed plate adjustably mounted on said frame beneath said hammer, an anvil mounted on the bed plate, said mounting permitting the anvil to move in a circular path around the axis of the hammer and preventing turning of the anvil, clamps for holding a piece of work on the anvil, and means for starting and stopping the reciprocation of the hammer.

20. A flange flattening machine comprising a stationary bed plate, a movable bed plate mounted thereon and adapted to be moved in a translating motion over a predetermined path on the stationary plate, an anvil mounted on said movable plate, spring pressed registering pins for locating work on said anvil, clamps for holding work on the anvil, a hammer disposed with its axis substantially in register with said path, and means for reciprocating said hammer longitudinally of its axis to engage work upon the anvil.

21. In a flange flattening machine, a movable bed plate, a stationary bed plate, means for guiding said movable plate in a translatory motion over a predetermined path on said stationary plate to bring the flange under the hammer, an anvil on said movable plate, a stationary reciprocating hammer, spring pressed pins for locating work on said anvil, and clamps for holding work on said anvil.

22. In a flange flattening machine, a bed plate, an anvil mounted on said bed plate, said anvil having a flat working surface, means for holding a plate like piece of work upon said anvil, and a plurality of spring pressed pins projecting above said anvil and above the upper surface of the plate like piece of work, said pins being adapted to engage the edge of the work to locate the work upon the anvil.

23. In a machine for flattening the margin of a thin plate like piece of work, the edge of which does not lie in a plane, the comb

of a flat anvil, said curve having a hole therein, a stop pin set in said hole, a spring for projecting the pin above the surface of the anvil a distance in excess of the thickness of the piece to be flattened so as to be capable of engaging the distorted edge when the piece lies on the anvil, and a flattening hammer for striking the margin of the piece to flatten the same, said pin receding against its spring when struck by the flattening hammer and following the hammer to flatten the edges which the pin engages.

In witness whereof, I hereunto subscribe my name this 10th day of February, 1930.

GEORGE SPATTA.
